RAILWAY TRAFFIC CONTROLLING
APPARATUS

Harold L. Ludwig, Wilkinsburg, Pa., assignor to
The Union Switch & Signal Company, Swiss-
vale, Pa., a corporation of Pennsylvania

Application May 26, 1938, Serial No. 210,235

20 Claims. (Cl. 246—134)

My invention relates to railway traffic controlling apparatus, and particularly to apparatus of the type involving railway switches capable of arrangement to form various traffic routes, and signals for governing traffic movements over the routes.

One feature of my invention is the provision of means for arranging one or more main railway traffic routes in an interlocking system, and of 10 means responsive to traffic conditions on the trailing side of a switch on each main route, such, for example, as occupancy by a train, for arranging said switch to establish a corresponding auxiliary or run-around route for succeeding 15 traffic movements.

The apparatus of my invention is an improvement over that disclosed in the copending applications Serial No. 323,286, filed December 3, 1928 by Lester E. Spray for Multiple control apparatus; Serial No. 416,061, filed December 23, 1929, by Howard A. Thompson for Multiple control apparatus; Serial No. 561,422, filed September 5, 1931, by Lester E. Spray for Multiple control apparatus; Serial No. 118,609, filed December 31, 1936, by John M. Pelikan for Railway traffic controlling apparatus; and Serial No. 201,740, filed April 13, 1938, by Henry S. Young for Railway traffic controlling apparatus.

I shall describe several forms of apparatus embodying my invention, and shall then point out 30 the novel features thereof in claims.

In the accompanying drawings, Figs. 1 to 6, inclusive, are diagrammatic views showing a track layout with switches and signals, and showing 35 control means for arranging various main and auxiliary traffic routes and for clearing the signals for the routes, in one form of apparatus embodying my invention; Fig. 1a is a diagrammatic view showing a modification of a portion of the apparatus shown in Fig. 1; Fig. 1aa is a 40 diagrammatic view showing a modification of a portion of the apparatus shown in Fig. 1a; Figs. 1A to 7A, inclusive, are diagrammatic views showing the same track layout as Figs. 1 to 6, but 45 with a different signal adjacent switch 3, and with different control means, in another form of apparatus embodying my invention; Fig. 1Aa is a diagrammatic view showing a modification of a portion of the apparatus shown in Fig. 1A; 50 and Fig. 2Aa is a diagrammatic view showing a modification of a portion of the apparatus shown in Fig. 2A, for use with Fig. 1Aa.

Similar reference characters refer to similar parts in each of the views.

55 In each of the views, the contacts operated by

the various relays or other devices are identified by numbers, such numbers having distinguishing prefixes from which they are separated by a dash when the contacts are shown apart from the relay or other device by which they are operated. The prefix for each of these contact numbers comprises the reference character for the respective relay or other device by which the associated contact is operated. For example, contact 6TR—81, shown in the control circuit 5 for relay MTE in Fig. 3, is identified by the number 81 separated by a dash from the prefix 6TR which is the reference character for relay 6TR by which this contact is operated. Similarly, contact 3V—156, shown in the circuit for magnet 3N in Fig. 6A, is identified by the number 156 separated by a dash from the prefix 3V which is the reference character for a ground lever by which this contact is operated.

Referring first to Fig. 1, a stretch of single track railway is shown at the left of the drawing adjoining a stretch of double track railway on the right. The lower rail of the single track stretch, as shown in the drawing, and the lower rail of each track in the double track stretch are 10 divided by insulated joints 8 to form sections A1T, 1T, 2T, A6T, 6T, B7T, A7T and 7T. A track transformer T having a primary winding 9 and a secondary winding 10 is provided for 15 each track section. The primary winding 9 of each of these transformers is constantly connected with the terminals BX and CX of a suitable source of current, not shown in the drawings. The secondary winding 10 of a transformer T is connected across the rails adjacent one 20 end of each track section, and a track relay, designated by the reference character R with a prefix comprising the reference character for the associated track section, is connected across 25 the rails adjacent the opposite end of each section. 30

A slow release relay 1TPR is controlled by a front contact of track relay 1TR.

A track switch 3 is located at the junction of the single track stretch with the double track 45 stretch for directing traffic movements from the single track stretch on the facing side of this switch to the upper or lower track of the double track stretch on the trailing side of this switch, as shown in the drawing, according as switch 3 50 occupies the normal position in which it is shown, or occupies the reverse position. These two switch positions may also be termed first and second positions. The upper and lower tracks of the double track stretch are interconnected by 55

means of a crossover track having, at one end, a power operated switch 4 located in section A1T, and having, at the other end, a spring switch located in section 7T. The upper and lower tracks are also interconnected by a second crossover track having, at one end, a power operated switch 5 located in section A7T, and having, at the other end, a spring switch located in section 6T.

10 It will be seen that with the track layout shown, a plurality of routes is provided having a common route end in the single track stretch.

Each of the switches 3, 4 and 5 is operated by a mechanism controlled by three magnets designated by the reference characters L, N and R with a distinguishing prefix which comprises the reference number of the switch. The mechanism for operating switch 3, for example, is controlled by magnets 3L, 3N and 3R.

20 Operated in conjunction with each of the switches 3, 4 and 5, is an indication circuit controller RL having pole changing contacts 12 and 13 which occupy a first or a second position according as the corresponding switch is in its first or second position, respectively. Each of the circuit controllers RL, by its contacts 12 and 13, controls a polarized indication relay designated by the reference character WPR with a prefix corresponding to the number of its switch. Relay 3WPR, for example, is controlled by circuit controller RL for switch 3.

A signal designated by the number 1 is located adjacent the adjoining ends of sections A1T and 1T, and a second signal designated by the number 2 is located adjacent the adjoining ends of sections 1T and 2T for governing traffic movements on the single track stretch toward the double track stretch. Lamps G of these signals are for traffic movements to section 6T, and lamps Y are for traffic movements to section 7T. A third signal 6 governs traffic movements on the upper track of the double track stretch, and a fourth signal 7 governs traffic movements on the lower track of the double track stretch. As shown in the drawings, each of the signals 1, 2, 6 and 7 may be of the color light type, each of signals 1 and 2 having a green lamp G, a yellow lamp Y, and a red lamp R, while signal 6 has a green lamp G and a red lamp R, and signal 7 has a yellow lamp Y and a red lamp R.

55 Operation of the switches and signals is controlled by a timing device or mechanism M having a rotor 16 which is set into operation by an approaching train entering section A1T. Rotor 16 is equipped with a contact finger or member 18 which, as shown in the drawing, is in engagement with a contact segment 19. Rotor 16 also has additional contact segments 20, 21 and 22.

60 Rotor 16, upon being set into operation, rotates in a direction which I shall assume to be as shown by the arrow, and similarly rotates its contact segments 19, 22, 20 and 21, thereby bringing these segments successively, in the order named, into engagement with the contact finger 18. Lamp G of signal 1 will be lighted while finger 18 is in engagement with segment 19; lamp R will be lighted while finger 18 is in engagement with segment 22; lamp Y will be lighted while finger 18 engages segment 20; red lamp R will again be lighted when finger 18 engages segment 21; and then this cycle of operation will begin again with the lighting of lamp G 75 when finger 18 again engages segment 19.

If a car or train enters section 1T while lamp G of signal 1 is lighted, a relay 1GPR becomes energized, and if a car or train enters section 1T while lamp Y is lighted, a second relay 1YPR will become energized.

Assuming, for example, that the traffic on the single and double track stretches shown consists of electric cars or trains, if a car or train is to proceed from the rear of signal 1 to section 6T, the motorman will operate his car or train so that it will enter section 1T in advance of signal 1 while lamp G of signal 1 is lighted, but if the car or train is to proceed to section 7T, the motorman will operate it so that it will enter section 1T while lamp Y of signal 1 is lighted. As soon as the car or train enters section 1T, relay 1TR will become deenergized, causing relay 1GPR or relay 1YPR to become energized and to remain energized according as the car or train enters section 1T while lamp G or lamp Y of signal 1 is lighted.

Fig. 1a shows an arrangement for controlling the energization of relays 1YPR and 1GPR manually by push button circuit controllers 1G, 1Y and 1GY instead of by the movement of a car or train into section 1T as in Fig. 1. Fig. 1aa shows a modification of the arrangement shown in Fig. 1a, if a lever or switch 1V is used instead of the push button circuit controllers 1G and 1Y shown in Fig. 1a for controlling relays 1YPR and 1GPR. With the arrangement of the apparatus for controlling relays 1GPR and 1YPR as shown in Figs. 1a and 1aa, the lighting circuits for signal 1 will be as shown in Fig. 1a instead of as shown in Fig. 1.

Fig. 2 shows route relays for controlling operation of the switches. One such route relay is provided for a main traffic route to section 6T over switches 3 and 4 normal. A second route relay is provided for an auxiliary traffic route associated with this main traffic route, to section 6T over switches 3 and 5 reversed. A third route relay is provided for a second main traffic route to section 7T over switch 3 reversed and 5 normal. A fourth route relay is provided for a second auxiliary traffic route associated with the second main traffic route, to section 7T over switch 3 normal and switch 4 reversed.

The route relays are controlled, in part, by relays 1GPR and 1YPR. Hence, when relay 1GPR or relay 1YPR becomes energized due to a train entering section 1T, a corresponding route relay will become energized for arranging the switches in the positions necessary for a corresponding route.

In Fig. 3, circuits are shown for two slow pick-up time element relays ATE and MTE. Energization of either of these relays is caused by a car or train which has proceeded beyond or in advance of switch 3 and occupies section B1T or A6T on the trailing side of this switch.

If a first car or train occupies section B1T or section A6T long enough for relay ATE or MTE, respectively, to pick up, a route relay for a corresponding auxiliary route will become energized, and a second car or train having the same destination as the first car or train will pass signals 1 and 2, as did the first train, with the Y lamps or the G lamps, respectively, of signals 1 and 2 lighted, but proceeding over the corresponding auxiliary route.

Fig. 4 shows circuits for controlling signal control relays 2HR, 6HR and 7HR for signals 2, 6 and 7, respectively.

Fig. 5 shows switch stick relays controlled by 75

an approaching car or train for controlling switches 3, 4 and 5 in accordance with the route the car or train is to take, as determined by the motorman's operation of the car or train for passing signal 1.

In Fig. 6, circuits are shown for controlling the switch magnets N, R and L, which are shown also in Fig. 1, for switches 3, 4 and 5.

Referring now to Figs. 1A to 7A, signal 2, shown in Fig. 1A, comprises two groups of lamps 2A and 2B instead of only one group as in Fig. 1. Green lamp G of signal 1 is for traffic movements to section 6T as in Fig. 1, and yellow lamp Y of signal 1 is for traffic movements to section 7T as in Fig. 1. The yellow lamp Y of the upper group 2A of signal 2 is for the main traffic route over switch 3 reversed and switch 5 normal, whereas lamp G of group 2A of signal 2 is for the auxiliary traffic route over switch 3 in its normal position and switch 4 reversed. Lamp G of the lower group 2B of signal 2 is for the main traffic route over switches 3 and 4 in the normal position, and yellow lamp Y of the lower group 2B of signal 2 is for the auxiliary route over switches 3 and 5 reversed.

Two additional relays 1GPR and 1YPR are shown in Fig. 1A, controlled by contact segments 21 and 22, respectively, of device M. Relays 1GPR and 1YPR are here controlled by segments 19 and 20, respectively, as in Fig. 1, but are controlled differently by other means.

Ground levers, designated by the reference characters 3V, 4V and 5V, are shown in Fig. 1A for controlling the switches locally if desired.

The main differences between the Figs. 2A to 7A, inclusive, and Figs. 2 to 6, inclusive, are that: In Fig. 3A, two additional relays ATER and MTER are provided, and relays ATE and MTE are controlled by the additional relays through circuits otherwise similar to the circuits in Fig. 3; contacts of the ground levers 3V, 4V and 5V are used in the circuits shown in Figs. 4A and 6A; and Fig. 7A shows the control of an additional relay 2PBSR. The purpose of relay 2PBSR is to permit a second car to follow a preceding car into section A1T, and then permit a third car to run around the first and second cars by the auxiliary route to section 7T.

Referring finally to Figs. 1Aa and 2Aa, the method of controlling relays 1GPR and 1YPR is different from that provided by Fig. 1A. The device M shown in Fig. 1A has here been replaced by a plurality of time element relays 1GTE, 1YTE and 1RTE for controlling relays 1GPR, 1YPR, 1GPR and 1YPR. Fig. 2Aa shows a modification of the arrangement shown in Fig. 2A, necessitated by the changes shown in Fig. 1Aa from the arrangement shown in Fig. 1A.

Having described, in general, the arrangement and operation of various forms of apparatus embodying my invention, I shall now trace in detail the operation of the apparatus.

As shown in the drawings, all parts of the apparatus are in the normal condition, that is, the various track sections are unoccupied, and hence the track relays and relay 1TPR are energized; the switches are in a first or normal position; the signals shown in Figs. 1, 1a, and 1Aa are unlighted, whereas in Fig. 1A the G lamp of signal 1 is lighted and the R lamps of signal 2 are lighted; devices M are deenergized; relays 6HR and 7HR are energized; switch indication relays 3WPR, 4WPR and 5WPR are energized in the normal direction; all other relays and the switch magnets are deenergized; and all levers

and push buttons are in their normal positions.

I shall first trace the operation of the form of apparatus shown in Figs. 1 to 6, inclusive.

With circuit controller RL of switch 3 in the normal position, control winding 23 of switch indication relay 3WPR is energized in the normal direction; local winding 24 of this relay is constantly connected to terminals BX and CX, and is therefore constantly energized; and hence the polar contacts of relay 3WPR are closed in the normal position. Relays 4WPR and 5WPR are similarly energized.

With track relay 1TR energized, the slow release repeater relay 1TPR is energized by a circuit including front contact 11 of track relay 15 1TR.

As shown in Fig. 4 of the drawings, relays 6HR and 7HR are normally energized. Relay 6HR is energized by a circuit passing from terminal BX, through contact 4WPR-25, contact 5WPR-29 in multiple with a branch path which includes contacts 7TR-26, B1TR-27 and A1TR-28 in series, and the circuit then passing through contacts 3R5RR-30 and 6TR-31, and the winding of relay 6HR to terminal CX. Relay 7HR is energized by a circuit passing from terminal BX, through contact 5WPR-32, contact 4WPR-35 in multiple with a path through contacts 6TR-33 and A6TR-34 in series, and the circuit then passing through contacts 3N4RR-36 and 7TR-37, and the winding of relay 7HR to terminal CX.

I shall assume that a car enters the approach section A1T, and that this car is to take the main route over switches 3 and 4 in the normal positions, in which they are shown, to section 6T. When the car enters section A1T, device M becomes energized by a circuit passing from terminal BX, through contacts A1TR-14 and 2TR-15, and rotor 16 to terminal CX. At the same time, lamp G of signal 1 becomes lighted by a circuit passing from terminal BX through contacts A1TR-14, 2TR-15, and 1TPR-17, finger 18 and contact segment 19 of device M, front point of contact 1TR-38, and lamp G of signal 1 to terminal CX.

If the car occupies section A1T for a sufficient period of time before entering section 1T, device M will move segment 19 out of engagement with contact finger 18, and will move segment 22 into engagement with finger 18. With finger 18 in engagement with segment 22, red lamp R of signal 1 will become lighted by a circuit passing from terminal BX, through contacts A1TR-14, 2TR-15, and 1TPR-17, finger 18 in engagement with segment 22, contacts 1TR-40 and 2TR-41, and lamp R to terminal CX. As device M is operated further, segment 22 leaves finger 18, and segment 20 engages finger 18, causing a circuit to be completed for lighting lamp Y of signal 1, 60 this circuit passing from terminal BX, through contacts A1TR-14, 2TR-15, and 1TPR-17, finger 18, segment 20, the front point of contact 1TR-42, and lamp Y of signal 1 to terminal CX. As mechanism M is operated still further, segment 20 leaves finger 18, and segment 21 engages finger 18, causing red lamp R to again become lighted by a circuit which is the same as the circuit previously traced for this lamp except that contact segment 21 instead of segment 22 70 now engages finger 18.

Since I have assumed that the car is to take the main route over switches 3 and 4 in the normal positions, the motorman will move the car past signal 1 while signal 1 is displaying the green 75.

5 indication. Relay 1TR will therefore become deenergized, thereby opening, at the front point of contact 1TR-38, the circuit for lamp G of signal 1, and completing, at contact 1TR-40, a third circuit for lighting lamp R, this circuit passing from terminal BX, through contact A1TR-39, back point of contact 1TR-40, contact 2TR-41, and lamp R to terminal CX.

10 Relay 1TR, upon becoming deenergized, also completes a pick-up circuit for energizing relay 1GPR, this circuit following the path previously traced for green lamp G of signal 1 as far as segment 19 of device M, and then passing through the back point of contact 1TR-38, and the winding of relay 1GPR to terminal CX. Relay 1GPR, upon becoming energized, completes its stick circuit passing from terminal BX, through contact 1TR-43, contact 44 of relay 1GPR, and the winding of relay 1GPR to terminal CX. The 15 20 pick-up circuit for relay 1GPR will be opened as soon as slow release relay 1TPR has opened its contact 1TPR-47, but relay 1GPR will then remain energized by its stick circuit.

25 Device M will be deenergized as soon as the car leaves section A1T, permitting contact A1TR-44 to open.

30 With relay 1GPR energized, route relay 3N4NR, shown in Fig. 2, will become energized by a circuit passing from terminal BX, through contacts 2HR-46, 2TR-47, 1GPR-48, the front point of contact A6TR-49, and MTE-50, and the winding of relay 3N4NR to terminal CX. Relay 3N4NR, upon becoming energized, will complete its stick circuit passing from terminal BX, 35 through contact 1TR-51, contact 53 of relay 3N4NR, and the winding of relay 3N4NR to terminal CX.

40 At the same time that relay 1GPR becomes energized, relay 3SR, shown in Fig. 5, also becomes energized by a circuit passing from terminal BX, through the front point of contact 2TR-54, contact 1TR-55, and the winding of relay 3SR to terminal CX.

45 With relay 3SR energized, a second switch stick relay 4NSR, shown in Fig. 5, will become energized by a circuit passing from terminal BX, through the front point of contact A6TR-57, contacts 3SR-58 and 3N4NR-59, and the winding of relay 4NSR to terminal CX.

50 Switch magnet 3N, shown in Fig. 6, will now be energized by a circuit passing from terminal BX, through contacts 3SR-61 and 3N4NR-62, and magnet 3N to terminal CX. Switch magnet 4N will also be energized by its circuit passing from terminal BX, through contact 4NSR-63, and magnet 4N to terminal CX. Since switches 3 and 4 are already in their normal positions, the energization of magnets 3N and 4N causes no change in the positions of these switches.

60 Signal control relay 2HR, shown in Fig. 4, will now be energized by a circuit passing from terminal BX, through contact 3SR-64, contacts 3WPR-65 and 4WPR-66 each closed in the left-hand position, contacts 3N4NR-68 and 65 2TR-72, and the winding of relay 2HR to terminal CX. When relay 2HR becomes energized, lamp G of signal 2 becomes lighted by a circuit passing from terminal BX, through contact 1TR-73, front point of contact 2HR-74, contact 1GPR-75, and lamp G of signal 2 to terminal CX.

70 When the car passes signal 2, relay 2TR will become deenergized, permitting its contact 2TR-75 to open the circuit previously traced for device M, thereby preventing device M from be-

ing energized by a following car entering section A1TR while the first car occupies section 2T. When relay 2TR becomes deenergized, its contact 2TR-72 opens the circuit traced for relay 2HR which then at the front point of its contact 2HR-74, opens the circuit traced for lamp G of signal 2 and, at the back point of this contact completes a circuit for lighting lamp R of signal 2, this circuit passing from terminal BX, through contact 1TR-73, back point of contact 2HR-74, and lamp R to terminal CX. At the same time, contact 2TR-47 opens in the pick-up circuits for the route relays shown in Fig. 2, thus preventing energization of the pick-up circuit for any of these relays as long as the car occupies section 2T. Relay 2TR, upon becoming deenergized, opens the pick-up circuit previously traced for relay 3SR, but, through the back point of its contact 2TR-54, closes a stick circuit for this relay, passing from terminal BX, 20 through the back point of contact 2TR-54, contact 56 of relay 3SR, and the winding of relay 3SR to terminal CX. Relay 3SR will therefore remain energized by its stick circuits while the car occupies section 2T. 25

30 Relay 2TR, upon becoming deenergized, completes a fourth circuit for lighting lamp R of signal 6, this circuit being the same as the third circuit, previously traced, except including the back point of contact 2TR-41 instead of contact 1TR-40. Relay 2TR, upon becoming deenergized, also completes a circuit for lighting lamp G of signal 6, this circuit passing from terminal BX, through contact 2TR-77, contact 3WPR-78 closed in the left-hand position, front point of contact 6HR-80, and lamp G of signal 6 to terminal CX. Relay 2TR also, upon becoming deenergized, closes a second stick circuit for relay 3N4NR, which is the same as the stick circuit previously traced for this relay except including contact 2TR-52 instead of contact 1TR-51.

35 When the car enters section A6T, relay A6TR becomes deenergized, opening the pick-up circuit previously traced for relay 4NSR, but closing the stick circuit for this relay, passing from terminal BX, through the back point of contact A6TR-57, contact 60 of relay 4NSR, and the winding of relay 4NSR to terminal CX. Deenergization of relay A6TR also closes a second circuit for lighting lamp G to signal 6, this circuit passing from terminal BX, through contact A6TR-79, front point of contact 6HR-80, and lamp G of signal 6 to terminal CX. Deenergization of relay A6TR also closes a circuit for energizing slow pick-up relay MTE, but if the car enters section 6T soon enough, this circuit will be opened before relay MTE closes its front contacts. 55

40 I shall next assume that a first car goes into section A6T and then stops to let a following car pass around it by means of the auxiliary route including switches 3 and 5 reversed. With the car occupying section A6T, the circuit is completed for energizing slow pick-up relay MTE, this circuit passing from terminal BX, through contacts 6TR-81, and A6TR-82, and the winding of relay MTE to terminal CX. Relay MTE will then open its back contacts and, upon the lapse of a measured period of time, the length of which is determined by the construction of relay MTE, this relay will close its front contacts, thereby completing a circuit for energizing route relay 3R5RR shown in Fig. 2, this circuit passing from terminal BX, through contacts 2HR-46, 2TR-47, and 1GPR-48, back point of contact 75

- 5 A6TR—49, contacts MTE—83, B7TR—84, A7TR—85, TTR—86 and 6TR—87, and the winding of relay 3R5RR to terminal CX. Relay 3R5RR, upon becoming energized, completes a circuit for energizing switch stick relay 5RSR, shown in Fig. 5, this circuit passing from terminal BX, through the front point of contact B7TR—89, contacts 3SR—90, and 3R5RR—91, and the winding of relay 5RSR to terminal CX.
- 10 With relay 3R5RR energized, a circuit will be completed for energizing magnet 3R shown in Fig. 6, this circuit passing from terminal BX, through contacts 3SR—61 and 3R5RR—94, and magnet 3R to terminal CX. At the same time, a circuit will be completed for energizing magnet 3L, this circuit passing from terminal BX through contact 3R5RR—95, contact 3WPR—99 closed in the left-hand position, and magnet 3L to terminal CX. With magnets 3L and 3R energized, switch 3 will be operated to the reverse position, causing contacts 12 and 13 of indication circuit controller RL of switch 3 to be closed in the reverse position, and thereby causing relay 3WPR to be energized in the reverse direction. During the movement of switch 3 from the normal to the reverse position, relay 3WPR will be deenergized, causing magnet 3L to be energized by a second circuit including contact 3WPR—100.
- 15 Energization of relay 5RSR completes a circuit for energizing magnet 5R shown in Fig. 6, this circuit passing from terminal BX, through contact 5RSR—101, and magnet 5R to terminal CX. At the same time, magnet 5L becomes energized by a circuit passing from terminal BX, through contact 5RSR—101, contact 5WPR—103 closed in the left-hand position, and magnet 5L to terminal CX. Switch 5 will therefore also be operated to its reverse position, and indication relay 5WPR will then become energized in the reverse direction similarly to relay 3WPR, thus opening, at its contact 5WPR—103, the circuit for magnet 5L.
- 20 With relays 3WPR and 5WPR now energized in the reverse direction, a second circuit will be completed for energizing relay 2HR, this circuit passing from terminal BX, through contact 3SR—64, contact 3WPR—65 closed in the right-hand position, contact 5WPR—67 closed in the right-hand position, contacts 3R5RR—69 and 2TR—72, and the winding of relay 2HR to terminal CX. Green lamp G of signal 2 will therefore become lighted as soon as a second car enters section 1T, the circuit for lighting lamp G being the same as previously traced.
- 25 With relay 3R5RR energized, the circuit previously traced for relay 6HR is now open at contact 3R5RR—30, and hence relay 6HR is deenergized. With relay 6HR deenergized, a circuit is complete for lighting red lamp R of signal 6, this circuit passing from terminal BX, through contact A6TR—79, back point of contact 6HR—80, and lamp R of signal 6 to terminal CX.
- 30 The second car, upon passing signal 2, causes relay 2TR to become deenergized, permitting its contact 2TR—72 to again open the circuit for relay 2HR which then becomes deenergized. With relay 2HR deenergized, a third car would cause the red lamp of signal 2 to be lighted by its circuit previously traced.
- 35 With relay 5WPR energized in the reverse direction, the circuits previously traced for energizing relay 7HR are open at contact 5WPR—32, and hence, upon the deenergization of relay 2TR, a circuit is completed for lighting lamp R of signal 7, this circuit passing from terminal BX,

through contact 2TR—77, contact 3WPR—78 closed in the right hand position, back point of contact 7HR—107, and lamp R of signal 7 to terminal CX.

When the second car enters section 1T, relay 5B7TR becomes deenergized, thereby opening the pick-up circuit traced for relay 5RSR, but completing a stick circuit for this relay, passing from terminal BX, through the back point of contact B7TR—89, contact 93 of relay 5RSR, and the winding of relay 5RSR to terminal CX. Upon the deenergization of relay B7TR, a second circuit is completed for lighting lamp R of signal 7, this circuit passing from terminal BX, through contact B7TR—105, back point of contact 7HR—107, and lamp R of signal 7 to terminal CX.

I shall now assume that all parts of the apparatus have been again returned to the normal conditions shown in the drawings, and that a car arriving on section 1T is to take the second main route over switch 3 reversed and switch 5 in its normal position. The motorman will therefore move this car into section 1T while lamp Y of signal 1 is lighted. Relay 1YPR will therefore become energized by a circuit which is the same as the circuit previously traced for lamp Y of signal 1 as far as contact segment 20 of device M, and thence passing through the back point of contact 1TR—42, and the winding of relay 1YPR to terminal CX. Relay 1YPR will then complete its stick circuit, passing from terminal BX, through contact 1TR—43, contact 45 of relay 1YPR, and the winding of relay 1YPR to terminal CX.

With relay 1YPR energized, a circuit will be completed for energizing route relay 3R5NR, this circuit passing from terminal BX, through contacts 2HR—46, 2TR—47 and 1YPR—108, front point of contact B7TR—109, contact ATE—110, and the winding of relay 3R5NR to terminal CX. This relay, upon becoming energized, completes its stick circuit passing from terminal BX, through contact 1TR—51, contact 111 of relay 3R5NR, and the winding of relay 3R5NR to terminal CX. As previously described, relay 3SR, shown in Fig. 5, becomes energized when the car enters section 1T. A circuit will now be complete for energizing switch stick relay 5NSR, this circuit passing from terminal BX, through the front point of contact B7TR—89, contacts 3SR—90 and 3R5NR—112, and the winding of relay 5NSR to terminal CX.

With relay 3R5NR energized, a second circuit will be completed for energizing magnet 3R, which is the same as the circuit previously traced except that it includes contact 3R5NR—114 instead of contact 3R5RR—94. Magnet 3L will also be energized by a third circuit which is the same as the first circuit previously traced for this magnet except including contact 3R5NR—96 instead of contact 3R5RR—95. Switch 3 will therefore be operated to the reverse position, causing relay 3WPR to be energized in the reverse direction. Magnet 5N will now be energized by a circuit passing from terminal BX, through the front point of contact 5NSR—102, and magnet 5N to terminal CX. Switch 5 will therefore remain in the normal position.

With switch 3 in the reverse position and switch 5 in the normal position, a third circuit will be completed for energizing relay 2HR, this circuit passing from terminal BX, through contact 3SR—64, contact 3WPR—65 closed in the right-hand position, contact 5WPR—67 closed in the left-hand position, contacts 3R5NR—70 and 75

2TR—12, and the winding of relay 2HR to terminal CX. With the car occupying section 1T, lamp Y of signal 2 will then become lighted by a circuit passing from terminal BX, through contact 1TR—73, front point of contact 2HR—74, and contact 1YPR—16, and lamp Y to terminal CX.

When the car enters section 2T, lamp Y of signal 7 will become lighted by a circuit passing from terminal BX, through contact 2TR—77, contact 3WPR—78 closed in the right hand position, front point of contact 7HR—107, and lamp Y of signal 7 to terminal CX.

When the car enters section B7T, a second circuit will be completed for lighting lamp Y of signal 7, passing from terminal BX, through contact B7TR—105, front point of contact 7HR—107, and lamp Y of signal 7 to terminal CX. If the car should stay long enough in section B7T, a second auxiliary route, including switch 3 in its normal position and switch 4 in its reverse position, would be arranged similarly to the manner in which the auxiliary route, including switch 3 reversed and switch 5 reversed, becomes arranged as previously described when a car occupies section A6T a given measured period of time.

When the car enters section A1T, a third circuit will be completed for lighting lamp Y of signal 7, which is the same as the second circuit previously traced for lighting this lamp except that it includes contact A1TR—106 instead of contact B7TR—105. A stick circuit will now also be completed for relay 5NSR, passing from terminal BX, through contact A1TR—92, contact 113 of relay 5NSR, and the winding of relay 5NSR to terminal CX.

As previously pointed out, route relays 1GPR and 1YPR may be controlled manually by means of push button circuit controllers as shown in Fig. 1a or by means of a lever or switch as shown in Fig. 1aa, instead of by the timing device M and the movement of the car into section 1T as in Fig. 1.

If, with the apparatus shown in Fig. 1a, a car is to move over the main route, including switches 3 and 4 in their normal positions, or over the associated auxiliary route, including switches 3 and 5 in the reverse positions, a leverman or trainman will depress the push button circuit controller 1G, thereby completing a pick-up circuit for relay 1GPR, passing from terminal BX, through contacts A1TR—115 and 1G, conductor 117, contact 118 of relay 1YPR, winding of relay 1GPR, and circuit controller 1GY to terminal CX. Relay 1GPR, upon becoming energized, completes its stick circuit passing from terminal BX, through contact A1TR—115, conductor 116, contact 122 or relay 1GPR, winding of relay 1GPR, and circuit controller 1GY to terminal CX. It will be noted that relay 1GPR does not become energized by the closing of circuit controller 1G until a car has arrived in section A1T, causing contact A1TR—115 to become closed due to the deenergization of relay A1TR.

With relay A1TR deenergized and relay 1GPR energized, a circuit will be completed for lighting lamp G of signal 1 as shown in Fig. 1a, this circuit passing from terminal BX, through contact A1TR—229, front point of contact 1GPR—230, and lamp G of signal 1 to terminal CX. The operation of the rest of the apparatus shown in Figs. 1 to 6, inclusive, will then be as previously described with relay 1GPR energized.

If, with the apparatus of Fig. 1 modified as shown in Fig. 1a, a car is to go over the second main route with switch 3 reversed and switch 5 in

the normal position, a leverman or trainman will depress circuit controller 1Y, completing a circuit for energizing relay 1YPR, passing from terminal BX, through contact A1TR—115, circuit controller 1Y, conductor 113, contact 120 of relay 1GPR, winding of relay 1YPR, and circuit controller 1GY to terminal CX. Relay 1YPR, upon becoming energized, completes its stick circuit, passing from terminal BX, through contact A1TR—115, conductor 116, contact 121 of relay 1YPR, winding of relay 1YPR, and circuit controller 1GY to terminal CX. The yellow lamp of signal 1 will then be lighted by a circuit passing from terminal BX, through contact A1TR—229, back point of contact 1GPR—230, front point of contact 1YPR—231, and lamp Y to terminal CX, as shown in Fig. 1a. The operation of the rest of the apparatus will then be as already described in connection with Figs. 1 to 6, inclusive.

If, after relay 1GPR or relay 1YPR is energized by the arrangement shown in Fig. 1a, it is desired to deenergize relay 1GPR or relay 1YPR, respectively, while a car is in section A1T, the leverman or trainman will depress circuit controller 1GY, thereby opening the stick circuit for relay 1YPR or relay 1GPR, whichever is energized.

If, instead of push button circuit controllers 1G and 1Y shown in Fig. 1a, a lever or switch 1V as shown in Fig. 1aa is used, a trainman or leverman, in order to complete the pick-up circuit for relay 1GPR between contact A1TR—115 and conductor 117, will move lever 1V to the left, closing contact 123 in its left-hand position, or in order to complete the pick-up circuit for relay 1YPR between contact A1TR—115 and conductor 118, the leverman or trainman will move lever 1V to the right, closing contact 123 of lever 1V in the right-hand position. The rest of the apparatus will then operate as described in connection with Fig. 1a.

I shall now describe the operation of the form of apparatus shown in Figs. 1A to 7A, inclusive.

Switch indication relays 3WPR, 4WPR and 5WPR, and signal control relays 6HR and 7HR are here normally energized similarly to the manner described for Figs. 1 to 6, inclusive.

With timing device M in the position shown in Fig. 1A, lamp G of signal 1 is lighted by a circuit passing from terminal BX, through contact finger 18 and segment 19 of device M, and lamp G of signal 1 to terminal CX. Lamp R of the upper group 2A of signal 2 is lighted by a circuit passing from terminal BX, through the back point of contact 2HR—124, and lamp R of group 2A to terminal CX. Lamp R of group 2B of signal 2 is also lighted by a circuit passing from terminal BX, through the back point of contact 2HR—126, and lamp R of group 2B to terminal CX.

The circuit by which relay 6HR is energized passes from terminal BX, through contact 5WPR—129 in multiple with contact A1TR—128, and then passing through contacts 3R5RR—130 and 6TR—131, and the winding of relay 6HR to terminal CX. The circuit by which relay 7HR is energized passes from terminal BX, through contact 4WPR—133 in multiple with contact A6TR—132, and then passing through contacts 3N4RR—134 and 7TR—135, and the winding of relay 7HR to terminal CX.

I shall assume that a car enters section A1T, and that this car is to proceed over the second main route, including switch 3 reversed and switch 5 in its normal position, to section 7T. With the car occupying section A1T, device M

will be operated by a circuit passing from terminal BX, through contacts A1TR-14 and 1TR-136, and device M to terminal CX.

Device M will therefore rotate segments 19, 20, 5 21 and 22 so that after a brief period of time, segment 19 will move out of engagement with finger 18 and segment 22 will come into engagement with finger 18, completing a circuit for relay 1YRPR. With relay 1YRPR thus energized, lamp R of signal 1 will be lighted by a circuit passing from terminal BX, through contact 139 of relay 1YRPR, and lamp R to terminal CX. As device M rotates still further, segment 22 will leave finger 18 and segment 20 will then come into engagement with contact finger 18, completing a circuit for lighting lamp Y of signal 1, passing from terminal BX, through contact finger 18, segment 20, back point of contact 2PBSR-138, and lamp Y to terminal CX. As device M rotates still further, segment 20 will leave finger 18 and segment 21 will come into engagement with finger 18, completing a circuit for relay 1GRPR. Relay 1GRPR, upon becoming energized, completes a circuit for again lighting lamp R of signal 1, this circuit passing from terminal BX, through contact 137 of relay 1GRPR, and lamp R to terminal CX. As device M rotates still further, segment 19 again engages finger 18, and the cycle of operations just described is repeated.

Since the car is to proceed over the second main route with switch 3 reversed and switch 5 in the normal position, the motorman will move his car past signal 1 while lamp Y of signal 1 is lighted. The car, upon entering section 1T, causes relay 1TR to become deenergized, which permits its contact 1TR-136 to open, and thereby stop the operation of device M.

Since the car has entered section 1T while lamp Y of signal 1 is lighted, contact finger 18 is engaging segment 20, and hence a circuit is now completed for energizing relay 1YPR. This circuit passing from terminal BX, through finger 18, segment 20, conductor 140, back point of contact 141 of relay 1YRPR, contact 142 of relay 1GPR, 40 contact 1TR-143, and winding of relay 1YPR to terminal CX. With relay 1YPR energized, a circuit is completed for energizing relay 3R5NR, shown in Fig. 2A, this circuit passing from terminal BX, through contacts 2TR-144 and 1YPR-145, front point of contact A7TR-146, 45 contacts ATE-147, ATER-148, 3N4RR-150, 3N4NR-151, and the winding of relay 3R5NR to terminal CX. With relay 3R5NR energized, switch stick relay 5NSR, shown in Fig. 5A, will 50 become energized by a circuit passing from terminal BX, through the front point of contact A7TR-153, contact 3R5NR-154, and the winding of relay 5NSR to terminal CX.

Switch magnet 3R, shown in Fig. 6A, will be 55 energized by a circuit passing from terminal BX, through contacts 3V-156 and 3R5NR-157, and magnet 3R to terminal CX. At the same time, magnet 3L will be energized by a circuit passing from terminal BX, through contacts 3V-156 and 3R5NR-157, contact 3WPR-158 closed in the 60 left-hand position, and magnet 3L to terminal CX. Switch 3 will therefore be operated to the reverse position, causing relay 3WPR to become energized in the reverse direction. With relay 5NSR energized, switch magnet 5N will be energized by a circuit passing from terminal BX, through contacts 5V-160 and 5NSR-161, and magnet 5N to terminal CX.

Signal control relay 2HR will now be energized 65 by a circuit passing from terminal BX, through

contact 3V-162, contact 3WPR-163 closed in the right-hand position, contact 5V-164, contact 5WPR-165 closed in the left-hand position, contacts 5NSR-166, 3R5NR-167 and 2TR-172, and the winding of relay 2HR to terminal CX. 5 With relay 2HR energized, lamp Y of upper group 2A of signal 2 will be lighted by a circuit passing from terminal BX, through the front point of contact 2HR-124, front point of contact 1YPR-125, contact 3R5NR-173, and lamp Y of 10 group 2A to terminal CX. Also, with relay 2HR energized, a stick circuit is completed for relay 3R5NR, passing from terminal BX, through contact 2HR-232, contact 152 of relay 3R5NR, and the winding of relay 3R5NR to terminal CX. 15

When the car enters section 2T, a second stick circuit is completed for relay 3R5NR, which is the same as the first stick circuit except that it includes contact 2TR-233 instead of contact 2HR-232. Relay 2HR is now deenergized because its circuit is opened by contact 2TR-172. Also, when the car enters section 2T, lamp Y of signal 7 will become lighted by a circuit passing from terminal BX, through contact 2TR-174, contact 3WPR-175 closed in the right-hand position, contact 5WPR-177, the front point of contact 7HR-178, and lamp Y of signal 7 to terminal CX.

When the car enters section A7T, a second circuit for lighting lamp Y of signal 7 will be closed, 30 passing from terminal BX, through contacts A7TR-176 and 5WPR-177, front point of contact 7HR-178, and lamp Y of signal 7 to terminal CX.

When the car leaves section 2T, the second stick circuit traced for relay 3R5NR is opened at contact 2TR-233, causing relay 3R5NR to become deenergized because its first stick circuit is already open at contact 2HR-232 and its pick-up circuit is open at the front point of contact 40 A7TR-146.

I shall assume that all parts of the apparatus are again in the normal condition, and that a car again enters the second main route but stops in section A7T. With the car in section A7T, a 45 circuit is completed for energizing relay ATER, shown in Fig. 3A, this circuit passing from terminal BX, through contacts 7TR-179 and A7TR-180, and the winding of relay ATER to terminal CX. Upon the energization of relay 50 ATER, a circuit is completed for energizing slow pick-up relay ATE, which is the same as the circuit traced for relay ATER as far as contact A7TR-180, and then passing through contact 181 of relay ATER, and the winding of relay ATE 55 to terminal CX.

Relay ATE will then open its back contacts, and, upon the lapse of a measured period of time, will close its front contacts, causing a circuit to be completed for the auxiliary route relay 3N4RR 60 when a following car energizes relay 1YPR, this circuit passing from terminal BX, through contacts 2TR-144 and 1YPR-145, back point of contact A7TR-146, contacts ATE-182, ASTR-183, 65 GTR-184, 7TR-185, 3R5NR-186, 3R5RR-187 65 and 2PBSR-188, and the winding of relay 3N4RR to terminal CX. With relay 3N4RR energized, the stick relay 4RSR shown in Fig. 5A will become energized by its pick-up circuit passing from terminal BX, through the front point of 70 contact A6TR-190, contact 3N4RR-191, and the winding of relay 4RSR to terminal CX.

Magnet 3N, shown in Fig. 6A, will now be energized by a circuit passing from terminal BX, through contacts 3V-156 and 3N4RR-193, and 75

- magnet 3N to terminal CX. Magnet 3L is now energized by a circuit passing from terminal BX, through contacts 3V-156 and 3N4RR-193, contact 3WPR-158 closed in the right hand position, and magnet 3L to terminal CX. With magnets 3N and 3L energized, switch 3 will be operated to the normal position. With relay 4RSR energized, magnet 4R will be energized by a circuit passing from terminal BX, through contacts 4V-194 and 4RSR-195, and magnet 4R to terminal CX. At the same time, magnet 4L will be energized by a circuit passing from terminal BX, through contacts 4V-194 and 4RSR-195, contact 4WPR-198 closed in the left-hand position, and magnet 4L to terminal CX. With magnets 4R and 4L energized, switch 4 will be operated by its mechanism to the reverse position, and relay 4WPR will then become energized in the reverse direction.
- 20 Relay 2HR will now become energized by a circuit passing from terminal BX, through contact 3V-162, contact 4WPR-163 closed in the normal position to the left, contact 4V-168, contact 4WPR-169 closed in the reverse position to the right, contacts 4RSR-170, 3N4RR-171 and 2TR-172, and the winding of relay 2HR to terminal CX. With relay 2HR energized, lamp G of the upper group 2A of signal 2 will now become lighted by a circuit passing from terminal BX, through the front point of contact 2HR-124, front point of contact 1YPR-125, contact 3N4RR-198, and lamp G of group 2A to terminal CX.

I shall next assume that all parts of the apparatus are again returned to the normal condition, and that a car moving over the second main traffic route stops in section A7T, and that it is desired to let a second car follow this car into section A7T so that a third car can run around both the first and second cars over switch 3 in the normal position and switch 4 in the reverse position to section 7T. Therefore, after the first car has entered section A7T and the second car has entered section 7T, a trainman or leverman will depress push button 2PB, causing a pick-up circuit to be completed for relay 2PBSR shown in Fig. 7A. Relay 2PBSR will be retained in the energized position, as long as the second car is in section 7T, by a circuit passing from terminal BX, through contact 1TR-199, contact 200 of relay 2PBSR, and the winding of relay 2PBSR to terminal CX.

When relay 2PBSR becomes energized, it opens the circuit for lamp Y of signal 1 at the back point of contact 2PBSR-138, and, at the front point of this contact, closes a third circuit for lamp R of signal 1. Relay 2PBSR, upon becoming energized, also opens the circuits for relay 3N4RR at its contact 2PBSR-188, thus preventing relay 3N4RR from being energized due to occupancy of section A7T by the first car. With relay 2PBSR energized, a second circuit will be completed for energizing relay 3R5NR, this circuit passing from terminal BX, through contact 2TR-144; contact 1YPR-145, back point of contact A7TR-146, contact 2PBSR-149, contacts 3N4RR-150 and 3N4NR-151, and the winding of relay 3R5NR to terminal CX. The route will therefore be arranged for the second car, as previously described for the first car, to proceed into section A7T.

When the second car leaves section 7T, relay 1TR will become energized, thereby opening the stick circuit for relay 2PBSR and causing this relay to become deenergized. The associated

auxiliary route, including switch 3 in the normal position and switch 4 in the reverse position, will now be arranged, as previously described, for the third car.

As previously stated, ground lever 3V, 4V and 5V, shown in Fig. 1A, are for the purpose of operating each of these switches individually, if desired. As an example of the operation of the switches under control of one of these ground levers, I shall assume that switch 3 is to be thus operated to its reverse position. A trainman or other operator will therefore move lever 3V to the reverse position, opening its normally closed contact 3V-156 in the circuits for the switch magnets, but closing its contact 3V-228 and thereby completing a circuit for magnet 3R shown in Fig. 6A, this circuit passing from terminal BX, through contact 3V-228, and magnet 3R to terminal CX. At the same time, magnet 3L will be energized by a circuit passing from terminal BX, through contact 3V-228, contact 3WPR-158 closed in the left-hand position, and magnet 3L to terminal CX. With magnets 3R and 3L energized, the mechanism of switch 3 will move this switch to the reverse position.

With the apparatus of Fig. 1A modified as shown in Fig. 1Aa, a car, upon entering section A7T, completes a circuit for energizing relay 1YTE, passing from terminal BX, through contacts A1TR-201, 1TR-202, 1RTE-203, 1YPR-204, 1GPR-205, back point of contact 1YRPR-206, and the winding of relay 1YTE to terminal CX. Upon the lapse of a measured period of time, characteristic of relay 1YTE, this relay will close its front contact 207, completing a pick-up circuit for relay 1YPR, passing from terminal BX, through contact 207 of relay 1YTE, contact 210 of relay 1GPR, and the winding of relay 1YPR to terminal CX. Relay 1YPR, upon becoming energized, completes its stick circuit passing from terminal BX, through contact 1YPR-208, contact 209 of relay 1YPR, contact 210 of relay 1GPR, and winding of relay 1YPR to terminal CX. With relay 1YPR thus energized while a car occupies section A7T, lamp Y of signal 1 will be lighted as shown in Fig. 1Aa, by a circuit passing from terminal BX, through contact 1TR-211, front point of contact 1YPR-212, back point of contact 2PBSR-213, and lamp Y of signal 1 to terminal CX. Relay 1YPR, upon becoming energized, opens the circuit for relay 1YTE at contact 1YPR-204. A circuit is then completed for energizing relay 1RTE, this circuit passing from terminal BX, through contacts A1TR-201, 1TR-202, 1YPR-214 and 1YTE-215, and the winding of relay 1RTE to terminal CX. Relay 1RTE, having a slow pick-up characteristic, does not at once close its front contact 216. If a car passes signal 1, opening contact 1TR-202 in the circuit for relay 1RTE before contact 216 of relay 1RTE closes, relay 1YPR will remain energized.

If another car subsequently enters section A7T, lamp Y will become lighted at once on account of relay 1YPR being still energized by the stick circuit previously traced. Upon the lapse of a given period of time determined by its slow pick-up characteristics, relay 1RTE will now pick up. A circuit will then be completed for energizing relay 1YPR, this circuit passing from terminal BX, through contact 216 of relay 1RTE, back point of contact 1GPR-219, and the winding of relay 1YRPR to terminal CX. Relay 1YRPR, upon becoming energized, opens, at its contact 1YRPR-208, the stick circuit for relay 1YPR,

causing relay 1YPR to become deenergized. A stick circuit for relay 1YRPR will then be completed, passing from terminal BX, through contact 1YPR-211, contact 218 of relay 1YRPR, back point of contact 1GPR-219, and the winding of relay 1YRPR to terminal CX.

With relay 1YPR deenergized, lamp R of signal 1 will become lighted by a circuit passing from terminal BX, through contact A1TR-211, back point of contact 1YPR-212, back point of contact 1GPR-224, and lamp R to terminal CX. With relay 1YRPR energized, a circuit will be completed for energizing relay 1GTE, this circuit following the same path as that previously traced for relay 1YTE as far as contact 1GPR-205, and then passing through the front point of contact 1YRPR-206, and the winding of relay 1GTE to terminal CX. Upon the lapse of a measured period of time, relay 1GTE will close its front contact 220, completing a pick-up circuit for relay 1GPR, passing from terminal BX, through contact 220, contact 223 of relay 1YPR, and the winding of relay 1GPR to terminal CX.

With relay 1GPR thus energized, lamp G of signal 1 will be lighted by a circuit passing from terminal BX, through contact A1TR-211, back point of contact 1YPR-212, front point of contact 1GPR-224, and lamp G of signal 1 to terminal CX. Relay 1GPR, upon becoming energized, opens its contact 1GPR-205 in the circuit for relay 1GTE, causing relay 1GTE to become deenergized, and also open its contact 1GPR-219 at the back point, deenergizing relay 1YRPR. A second circuit will now be completed for energizing relay 1 RTE, which is the same as the circuit previously traced for this relay except that it includes contacts 1GPR-234 and 1GTE-235 instead of contacts 1YPR-214 and 1YTE-215. If a train passes signal 1 now, the circuit for relay 1 RTE will be opened, thus preventing contact 216 of relay 1 RTE from closing. Relay 1GPR will therefore stay energized by its stick circuit.

The apparatus shown in Fig. 2Aa differs from that shown in Fig. 2A only by having contact 1GPR-227 connected in multiple with contact 1GPR-226, and in having contact 1YRPR-225 connected in multiple with contact 1YPR-145.

I have described, for a few typical traffic movements, the operation of the apparatus shown in the accompanying drawings embodying my invention. From those descriptions of operation and from the preceding general description, operation of each of the various forms of apparatus for every other possible traffic movement will be readily understood by reference to the drawings.

From the foregoing description and the accompanying drawings, it follows that in apparatus embodying my invention, I provide means controlled by railway traffic or by manually operable apparatus for arranging a plurality of main traffic routes, and provide means responsive to occupancy of each main traffic route by a car or train for a predetermined or measured time period for arranging a corresponding auxiliary traffic route. The means controlled by traffic for arranging the main route may employ a timing device M, as shown in Figs. 1 and 1A, or a plurality of time element relays, as shown in Fig. 1Aa.

Although I have herein shown and described only a few forms of railway traffic controlling ap-

paratus embodying my invention, it is understood that various changes and modifications may be made therein within the scope of the appended claims without departing from the spirit and scope of my invention.

Having thus described my invention, what I claim is:

1. In combination, a main railway route, an auxiliary railway route, a track switch having a first position for directing traffic movements over said main route and having a second position for directing traffic movements over said auxiliary route, manually operable means for effecting operation of said switch to said first position, and means responsive to the presence of a train on said main route on the trailing side of said switch for a measured period of time for effecting operation of said switch to said second position.

2. In combination, a main railway track, an auxiliary railway track, a track switch which in its normal position directs traffic movements along said main track and which in its reverse position directs traffic movements to said auxiliary track, means for effecting operation of said switch to its normal position, and means responsive to the presence of a first train on said main track on the trailing side of said switch jointly with the presence of a second train on said main track in the opposite direction from said switch for effecting operation of said switch to its reverse position.

3. In combination, a main railway track, an auxiliary railway track, a track switch which in its normal position directs traffic movements along said main track and which in its reverse position directs traffic movements to said auxiliary track, means controlled by a train on the facing side of said switch for effecting operation of said switch to its normal position, and means responsive to the presence of a train on said main track on the trailing side of said switch for selectively controlling said switch to occupy the normal or the reverse position in response to a second train on the facing side of said switch.

4. In combination, a main railway track, an auxiliary railway track, a track switch which in its normal position directs traffic movements along said main track and which in its reverse position directs traffic movements to said auxiliary track, means for effecting operation of said switch to its normal position, means responsive to the presence of a train on said main track on the trailing side of said switch for effecting operation of said switch to its reverse position, and manually controllable means for cancelling such effect of the presence of a train on said main track on the trailing side of said switch.

5. In combination, a stretch of railway track, a signal capable of displaying a plurality of indications for directing traffic movement on said track, a plurality of time element relays, means controlled by traffic conditions on said track to the rear of said signal for successively energizing said time element relays, and means controlled by said time element relays when thus energized for controlling said signal to display said indications successively.

6. In combination, a track layout for providing a plurality of main and auxiliary traffic routes beginning at a common route end, a manually controllable contact for each of said main routes, means controlled by a train at said common route end in cooperation with each of said manually controllable contacts for arranging a cor-

- responding main traffic route, and means controlled by a train occupying each main traffic route on the trailing side of said common route end for arranging a corresponding auxiliary traffic route.
7. In combination, a track layout for providing a plurality of main and auxiliary traffic routes having a common route end including a track switch, a route relay for each of said traffic routes, manually controllable means for each main traffic route cooperating with a train on the facing side of said switch for energizing the corresponding route relay, means for each main traffic route responsive to a train on the same main traffic route on the trailing side of said switch for energizing a route relay for a corresponding auxiliary traffic route, and means controlled by each route relay in the energized condition for arranging the corresponding main or auxiliary traffic route.
8. In combination, a track layout for providing a plurality of main and auxiliary traffic routes, a track switch common to said main and auxiliary traffic routes, means for arranging each of said main traffic routes, and means effective when each main traffic route is occupied for a measured period of time on the trailing side of said switch for arranging a corresponding auxiliary traffic route.
9. In combination, a railway track switch, a main traffic route and an auxiliary traffic route including said switch in its normal and reverse positions respectively, means responsive to the presence of a train on the facing side of said switch for arranging said main traffic route, and means controlled by traffic conditions on said main traffic route for arranging said auxiliary traffic route when said main traffic route is occupied on the trailing side of said switch for a measured period of time.
10. In combination, a railway track switch, a main traffic route and an auxiliary traffic route including said switch in its first and second extreme positions respectively, means for directing traffic movements over said main traffic route, and means responsive to traffic conditions on said main traffic route when said main traffic route is occupied on the trailing side of said switch for a measured period of time for directing traffic movements over said auxiliary traffic route.
11. In combination, a main railway track, an auxiliary railway track, a track switch interconnecting said main and auxiliary tracks, means for effecting operation of said switch to one of its extreme positions for arranging a main railway traffic route over said main track, and means set into operation by a car or train on said main track on the trailing side of said switch in cooperation with manually controllable means and a car or train on said main track on the facing side of said switch for effecting operation of said switch to its other extreme position for forming an auxiliary traffic route including said auxiliary track.
12. In combination, a main railway track, an auxiliary railway track, a track switch interconnecting said main and auxiliary tracks, means for effecting operation of said switch to one of its extreme positions for arranging a main railway traffic route over said main track, and time element means set into operation by a car or train on said main track on the trailing side of said switch for cooperating with other control means upon the lapse of a measured period of

time for effecting operation of said switch to its other extreme position for forming an auxiliary traffic route including said auxiliary track.

13. In combination, a main railway track, an auxiliary railway track, a track switch interconnecting said main and auxiliary tracks, a signal capable of displaying a first or a second indication for directing traffic movements on said main track toward said switch, means for controlling said signal to display said first and second indications alternately, a first and a second stick relay, means controlled by a car or train passing said signal in the direction of traffic movements governed by said signal for energizing said first or said second stick relay according as said car or train passes said signal while said signal is displaying said first or said second indication respectively, traffic controlled means for retaining each of said stick relays in the energized condition while a car or train occupies said main track within a given distance in advance of said signal, and means controlled by said first or said second stick relay in the energized condition for operating said switch to its first or second extreme position respectively.

14. In combination, a stretch of railway track including a switch, manually controllable means for effecting operation of said switch to its first and second extreme positions, and means set into operation by a car or train occupying a given portion of said stretch of track on the trailing side of said switch after moving over said switch in said first position for operating said switch to its second position after the lapse of a measured period of time.

15. In combination, a first railway route, a second railway route, a track switch having a first position for directing traffic movements over said first route and having a second position for directing traffic movements over said second route, means for effecting operations of said switch to its first and second positions, other means responsive to the presence of a train on said first route on the trailing side of said switch for effecting operation of said switch to its second position, and other means responsive to the presence of a train on said second route on the trailing side of said switch for effecting operation of said switch to its first position.

16. In combination, a first railway route, a second railway route, a track switch having a first position for directing traffic movements over said first route and having a second position for directing traffic movements over said second route, manually controllable means for effecting operation of said switch to its first and second positions, means responsive to the presence of a train on said first route on the trailing side of said switch for effecting operation of said switch to its second position, and means responsive to the presence of a train on said second route on the trailing side of said switch for effecting operations of said switch for effecting operation of said switch to its first position.

17. In combination, a first railway route, a second railway route, a track switch having a first position for directing traffic movements over said first route and having a second position for directing traffic movements over said second route, means responsive to the presence of a train on the facing side of said switch for effecting operations of said switch to its first and second positions, means responsive to the presence of a train on said first route on the

trailing side of said switch for effecting operation of said switch to its second position, and means responsive to the presence of a train on said second route on the trailing side of said switch for effecting operation of said switch to its first position.

18. In combination, a main railway track, an auxiliary track connected with said main track at one point, a switch for connecting the auxiliary track with the main track at another point, means for effecting operation of said switch to a first extreme position for arranging a main traffic route over said main track, and means responsive to the presence of a train on said main track between said one point and said switch after the lapse of a measured period of time for effecting operation of said switch to its other extreme position for arranging a run-around traffic route for said main track including said auxiliary track.

19. In combination, a main railway track, an auxiliary track connected with said main track at one point, a switch for connecting the auxiliary track with the main track at another point, means responsive to the presence of a train on said main track on the facing side of said switch for effecting operation of said switch to a first extreme position for arranging a main traffic route over said main track, and means responsive

to the presence of a train on said main track between said one point and said switch for effecting operation of said switch to its other extreme position for arranging a run-around traffic route for said main track including said auxiliary track. 5

20. In combination, a main railway track, an auxiliary track connected with said main track at one point, a switch for connecting the auxiliary track with the main track at another point, 10 means for effecting operation of said switch to a first extreme position for arranging a main traffic route over said main track, means responsive to the presence of a car or train on said main track between said one point and said switch jointly with manually controllable means for effecting operation of said switch to its first extreme position to permit a second car or train to occupy said main track between said one point and said switch contemporaneously with said 15 first train, and means responsive to the presence of said first and second cars or trains on said main track between said one point and said switch for effecting operation of said switch for arranging a run-around traffic route for said 20 main track including said auxiliary track. 25

HAROLD L. LUDWIG.

CERTIFICATE OF CORRECTION.

Patent No. 2,203,916.

June 11, 1940.

HAROLD L. LUDWIG.

It is hereby certified that error appears in the printed specification of the above numbered patent requiring correction as follows: Page 9, second column, line 61, claim 5, for the word "movement" read --movements--; page 10, second column, lines 60 and 64, claim 16, strike out "for effecting operation of said switch"; line 63, same claim, for "operations" read --operation--; and that the said Letters Patent should be read with this correction therein that the same may conform to the record of the case in the Patent Office.

Signed and sealed this 30th day of July, A. D. 1940.

(Seal)

Henry Van Arsdale,
Acting Commissioner of Patents.
